(57) **CLAIM**

The ornamental design for the fire alarm panel, substantially as shown and described.

DESCRIPTION

FIG. 1 is a front elevation view of a fire alarm panel according to a first embodiment of the present invention;

FIG. 2 is a top plan view of the fire alarm panel of FIG. 1;

FIG. 3 is a bottom plan view of the fire alarm panel of FIG. 1;

FIG. 4 is a left-side elevation view of the fire alarm panel of FIG. 1;

FIG. 5 is a right-side elevation view of the fire alarm panel of FIG. 1;

FIG. 6 is a rear elevation view of the fire alarm panel of FIG. 1;

FIG. 7 is a front elevation view of a fire alarm panel according to a second embodiment of the present invention;

FIG. 8 is a top plan view of the fire alarm panel of FIG. 7;

FIG. 9 is a bottom plan view of the fire alarm panel of FIG. 7;

FIG. 10 is a left-side elevation view of the fire alarm panel of FIG. 7;

FIG. 11 is a right-side elevation view of the fire alarm panel of FIG. 7;

FIG. 12 is a rear elevation view of the fire alarm panel of FIG. 7;

FIG. 13 is a front elevation view of a fire alarm panel according to a third embodiment of the present invention;

FIG. 14 is a top plan view of the fire alarm panel of FIG. 13;

FIG. 15 is a bottom plan view of the fire alarm panel of FIG. 13;

FIG. 16 is a left-side elevation view of the fire alarm panel of FIG. 13;

FIG. 17 is a right-side elevation view of the fire alarm panel of FIG. 13; and,

FIG. 18 is a rear elevation view of the fire alarm panel of FIG. 13.

It is understood that the front of the design is flat and planar, and the markings are understood to be surface indicia.

The broken lines showing features of the cabinet are included for the purpose of illustrating the environment of the fire alarm panel and form no part of the claimed design. The broken lines showing the speaker opening are included only for the purpose of illustrating a portion of the fire alarm panel and form no part of the claimed design.

1 Claim, 18 Drawing Sheets
